DIRECT ACTION KEYPUNCH

Nelson S. Welk and Charles O. Carpenter, Athens,
Ohio, assignors to The McBee Company,
Athens, Ohio, a corporation

Application April 21, 1945, Serial No. 589,517

6 Claims. (Cl. 164—112)

1

This invention relates to machines for punching or notching the marginal edges of cards, checks and the like.

It is the principal object of our present invention to provide an improved punching or notching apparatus of the character referred to which is of the key operated type, and in which the operation of a selected key both indexes and actuates the punching mechanism to effect punching or notching of a card, check or the like.

It is a further object of our invention to provide a machine of the character referred to which is simple in construction and which may be inexpensively produced, and which will be efficient in operation.

One form which the invention may assume is exemplified in the following description and illustrated by way of example in the accompanying drawings, in which:

Fig. 1 is a transverse sectional view taken on line 1—1 of Fig. 4, and showing the parts of the slotting mechanism in the position they assume when a selected key has been depressed.

Fig. 2 is a similar sectional view, showing the parts of the slotting mechanism in normal position.

Fig. 3 is a fragmentary view of the type of card to be operated upon by a machine such as here disclosed.

Fig. 4 is a plan view of the machine with parts broken away to more clearly disclose certain features of construction.

Fig. 5 is a vertical sectional view taken through the machine on line 5—5 of Fig. 2.

Referring more particularly to the accompanying drawings, 10 indicates a portable punching or notching machine for perforating or notching the marginal edges of cards, checks and the like at predetermined points along the marginal edge thereof. The type of cards or checks or other paper forms which are adapted to be punched or slotted by the device here disclosed are of the general type disclosed in United States patent to T. C. Andrews No. 2,181,165, dated November 28, 1939, and A. Perkins No. 1,544,172, dated June 30, 1925.

In general, cards or checks of that type are provided with a series of perforations adjacent one or more edges of the card. These perforations are arranged into fields, each field designating units, tens, hundreds, etc. These perforations are designed so that the material of the card or check which intervenes between the perforation and the marginal edge of the card may be entirely punched out or slotted away. This con-

2

struction permits one to pass a slotting device or needle through the perforations and on manipulating the needle, the cards which have not been slotted through at the selected perforation 5 will remain on the needle, while those which have been slotted will detach from the needle. The perforations are, of course, evenly spaced apart along the edge of the card, and it is the purpose of the present machine to enable the slotting 10 or punching of the cards from the perforation through the edge of the card to be accomplished by a keyboard type of machine.

In general, the machine comprises a frame structure which includes end frame members 11, 15 a casing 12 and end cover plates 14. The casing 12 is formed with a substantially horizontal keyboard 15 projecting upwardly from which are the keys 16. These keys are arranged in groups from right to left, each group comprising keys of the numbers 1, 2, 4 and 7 and corresponding with a field of similarly numbered perforations 17 on the card or check to be slotted, as illustrated in Fig. 3. When the card is correctly positioned in the machine, depression of the first group of keys on 20 the right will slot the corresponding field of perforations 17 at the right end of the card or check, and the depression of the second group of keys on the keyboard will similarly slot the next succeeding field on the card.

30 Arranged longitudinally and fixed to the end members 11 thereof is a rigid matrix bar 18 which is provided with a longitudinal card receiving slot 19 for the reception of the card. This slot extends downwardly from the upper surface of the matrix bar, as illustrated. The casing 12 of the machine is provided with a longitudinal slot 20 registering with and overlying the slot 19 in the matrix bar and is so formed as to constitute a guide to enable a card or check to be inserted 35 40 edgewise downwardly through the casing into the slot 19 of the matrix bar 18.

An aligning member 21 is fixed on the matrix bar adjacent the right-hand end thereof and provides means for properly registering or aligning 45 the card or check in the machine with respect to the slotting means. That is to say, when the card or check is inserted into the slot 19, through the guide opening 20, its right-hand edge is abutted against the aligning member 21 and thus 50 the card is properly positioned with respect to the punching or slotting means so that operation of the latter will correctly slot or notch the card or check in register with the proper perforation or perforations 17 of the card.

55 The matrix bar 18 is formed with a plurality

of female die sockets 22 spaced longitudinally of the matrix bar 18 so as to register with the perforations 17 of a card or check inserted into the machine for slotting or notching. That is to say, there is one female die socket 22 for each perforation along the edge of the card and in register therewith. The upper edge 23 of each die socket 22 is at an elevation above the lower end of the card receiving slot 19 sufficiently so that the upper edges of the sockets 22 are at the center line of the perforations 17 when a card or check is inserted into the card receiving slot 19. The width of each of the sockets 22 corresponds to the diameter of the perforations 17.

Pivottally mounted within each socket for oscillation in a plane transversely of the matrix bar 18 is a male die member 24, which male die members are independently pivoted on a pivot rod 25 which extends longitudinally through the matrix bar 18. At its upper end and extending radially from each male die member 24 is a projecting slotting die 26, which is integrally formed with the male die member 24. The side edges of this slotting die 26 are in shearing relationship with the adjacent sides of the female die socket 22. The shearing edges of the slotting die 26 are tangential with respect to the pivotal axis of the male die member 24 so that a shearing action results.

The male die member has an operating arm 27 extending radially therefrom in a direction substantially opposite the direction of extension of the slotting die 26 thereon. This operating arm is embraced by a yoke 28 connected by a tension spring 29 to the frame of the machine and constantly urges the male die member 24 to a position unobstructing the card receiving slot 19 by positioning the slotting die 26 to one side of that slot.

As before stated, one key 16 is associated with and operatively connected to each male die member 24. Each key 16 is fixed at the upper end of a key lever 30. This key lever has a vertically extending portion 31 and is right-angledly bent to provide a horizontally extending portion 32. The vertical portion 31 is guided in a slot 33 in the keyboard 15 for reciprocation therethrough. The horizontal portion 32 of the key lever is pivoted as at 34 to one leg of a crank arm 35, which crank arms are freely pivotal on a longitudinal rod 36 extending between the frame members 11 of the frame. The other leg of the crank arm 35 projects into the yoke 28 so that it will be operatively associated with the operating arm 27 of the male die 24. Obviously, when the key 16 is depressed, the vertical portion of the key lever 31 will move downwardly, depressing the connected end of the crank arm 35 and swinging the opposite leg of the crank arm in the directions of the arrows in Figs. 1 and 2. This movement will be imparted to the operating arm 27, turning the male die 24 about the pivot rod 25 and causing the slotting or notching die 26 thereof to notch the card which has been inserted in the card receiving slot 19. The swinging movement of the operating arm of the male die so operated will be limited by a stop rod 37 extending longitudinally between the end frames 11. The cuttings will be deposited on an apron 38 formed by an inturned section of the rear wall of the housing, as illustrated in Figs. 1 and 2, a discharge slot 39 being formed between this apron and the upper portion of the rear wall of the housing to

enable the cuttings to be discharged from the machine.

It is thus seen from the foregoing that a direct slotting or punching action is provided wherein depression of a selected key effects direct slotting or punching of a card or sheet inserted in the machine.

While we have shown the preferred form of our invention, it is to be understood that various changes may be made therein by those skilled in the art without departing from the spirit of the invention as defined in the appended claims.

Having thus described our invention, what we claim and desire to secure by Letters Patent is:

1. In a machine of the character described, a matrix bar, said matrix bar having a plurality of die sockets formed transversely therethrough, said matrix bar having card receiving means for receiving and positioning a card in correct position relative to said sockets, a male die member pivottally mounted in each socket for cooperation therewith to punch a card or sheet disposed for punching in said matrix bar, and an individual and separately operated key for each of the said male die members, operation of which key actuates the male die member.

2. In a machine of the character described, a fixed longitudinally disposed matrix bar, said matrix bar having a plurality of die sockets formed laterally thereof, said matrix bar having a longitudinal slot formed longitudinally thereof and extending inwardly thereof from its upper surface for receiving and positioning a card for punching relative to said die sockets, a male die member pivottally mounted in each die socket for cooperation therewith in punching a card positioned in said matrix bar, spring means normally maintaining said male die members in an ineffective position, a key associated with each male die member, and lever means connecting said key with its respective die member whereby operation of the key will actuate the die member.

3. In a machine of the character described, a frame, a matrix bar extending horizontally of the frame and fixed therein, said matrix bar having a plurality of die sockets formed transversely therein, said matrix bar being formed with a card receiving slot extending longitudinally thereof and inwardly from its upper surface, said slot being adapted to receive a card and position the same with respect to the sockets for punching, a male die member pivottally mounted in each socket for cooperation therewith in punching a card positioned for punching, a keyboard on the frame, a key projecting upwardly from said board for each male die member, lever means connecting each key with its respective die member whereby depression of the key will actuate the respective die member to effect a punching operation, and spring means for returning the die member and the key to normal position upon release of the key.

4. In a machine of the character described, a frame, a matrix bar extending horizontally of the frame and fixed therein, said matrix bar having a plurality of die sockets formed transversely therein, said matrix bar being formed with a card receiving slot extending longitudinally thereof and inwardly from its upper surface, said slot being adapted to receive a card and position the same with respect to the sockets for punching, a male die member pivottally mounted in each socket for cooperation there-

with in punching a card positioned for punching, a keyboard on the frame, a key projecting upwardly from said board for each male die member, lever means connecting each key with its respective die member whereby depression of the key will actuate the respective die member to effect a punching operation, spring means for returning the die member and the key to normal position upon release of the key, a casing for enclosing the matrix bar and the punching mechanism, said casing having a guide slot formed therein overlying the matrix bar in register with the card receiving slot therein, and means on said casing for receiving the punchings and discharging them from within the casing.

5. In a machine of the character described, a frame, a matrix bar extending horizontally of the frame and fixed therein, said matrix bar having a plurality of die sockets formed transversely therein, said matrix bar being formed with a card receiving slot extending longitudinally thereof and inwardly from its upper surface, said slot being adapted to receive a card and position the same with respect to the sockets for punching, a pivot rod extending longitudinally through the matrix bar, a male die member in each socket and pivoted on said rod for punching, a keyboard on the frame, a key projecting upwardly through said keyboard for each male die member, a lever for each key and male die, said lever being pivoted intermediate its ends to the frame and having one end connected with the key and the other end operatively engaging the male die whereby depression of the key will cause pivoting of the said male die member in its socket to effect a punching operation, a stop member extending horizontally of the frame positioned so as to limit the pivotal movement of said male die members and spring means for returning the male die member and associated lever and key to normal position upon release of the key.

6. In a machine of the character described, a frame, a matrix bar extending horizontally of the frame and fixed therein, said matrix bar

5 having a plurality of die sockets formed transversely therein, said matrix bar being formed with a card receiving slot extending longitudinally thereof and inwardly from its upper surface, said slot being adapted to receive a card and position the same with respect to the sockets for punching, a pivot rod extending longitudinally through the matrix bar, a male die member in each socket and pivoted on said rod for punching, a keyboard on the frame, a key projecting upwardly through said keyboard for each male die member, a lever for each key and male die, said lever being pivoted intermediate its ends to the frame and having one end connected with the key and the other end operatively engaging the male die whereby depression of the key will cause pivoting of the said male die member in its socket to effect a punching operation, a stop member extending horizontally of the frame positioned so as to limit the pivotal movement of said male die members, spring means for returning the male die member and associated lever and key to normal position upon release of the key, and a casing for enclosing the matrix bar and the punching mechanism, said casing having a guide slot formed therein overlying the matrix bar in register with the card receiving slot therein, and means on said casing for receiving the punchings and discharging them from within the casing.

20 30 NELSON S. WELK.
